UNITED STATES PATENT OFFICE.

WILLIAM ANDREW SPARKS, OF EDMONTON, ALBERTA, CANADA.

FRESH-AIR HEATER.

Application filed October 25, 1926. Serial No. 144,092.

This invention relates to improvements in fresh air heaters, and the objects of the invention are to provide a durable, light and simply constructed apparatus for heating and ventilating purposes.

Further objects are to provide a device of this description for introducing fresh warmed air into buildings and the like and designed to replace hot air furnaces now in use.

With the foregoing and other objects hereinafter more fully described in view, my invention consists of the novel combination, construction and arrangement of parts as described in the present specification and illustrated in the accompanying drawings which form part of the application.

The invention comprises a casing having an inner casing spaced therefrom and within the inner casing a chamber having a plurality of air and gas passageways therein, air being supplied to said chamber from the outside, and means communicating with the air and gas passageways respectively for discharging the heated air and gases on the inner chamber being heated.

Referring now to the drawings, in which like characters of reference indicate corresponding parts in each figure,

Figure 1 is a side elevation of my improved air heater;

Figure 2 is a plan view of the same.

Figure 3 is a longitudinal section taken through one of the waste gas fumes.

Figure 4 is a section on the line 4-4 of Figure 3.

Figure 5 is a section on the line 5-5 of Figure 3.

Figure 6 is a plan view of the radiating member.

Figure 7 is a fragmentary perspective view of the waste gas flues.

Figure 8 is a longitudinal section through one end of the gas flues.

Figure 9 is a longitudinal section through a modified type of air heater; and

Figure 10 is a perspective view showing the combustion chamber and radiating members which may be manufactured as individual units.

In the drawings, in which a preferred form of my invention is disclosed, 10 designates an outer casing of suitable material such as metal within which is an inner casing

11 spaced therefrom and within which are arranged longitudinally a plurality of flues 14 having therebetween air passageways 13.

These flues 14 are provided with baffles 27 so that the gases passing therethrough will be diverted before entering the exit flue 25. The opposite ends of the flues 14 communicate with a combustion chamber 28 in which is arranged a gas burner 15 or other suitable heating means.

It will thus be seen that the heat from the combustion chamber will pass through the flues 14 to heat them and through them the air in the passageways 13. From the flues the heated air flows into the header 24 and thence into the exit flue 25. At the opposite end of the apparatus is a fresh air intake 16 through which air enters the apparatus and travels in the passageways 13 between the flues 14 and thence out of the apparatus in preheated form for distribution through the hot air exit 18, see Figure 1.

Adjacent one end of the apparatus is a door 19 communicating with a chamber 20 in which may be placed a vessel or the like 21 to humidify, or disinfect, or perfume the air as may be desired as it passes thereover.

The fresh air intake 16 is provided with a baffle 22 for the purpose of controlling the air supply down and over the vessel 21 before entering the space 23.

The outer ends of the flues as shown in Figure 3, are sloped to more effectively deflect the heated air and gas entering therethrough so that the air in passing between the flues is directed upwardly towards the hot air outlet 18.

From the foregoing it will be seen that on the apparatus being connected up and the burner started, the flues communicating with the combustion chamber 28 will become heated and that the cold air being admitted from the opposite end of the apparatus and flowing between the heated flues will become heated as it passes along the passageways 13 and up into the hot air exit flue 18, the gas fumes eventually passing through the flues 14 into the header 24 through the short pipe openings 24^a and thence to the main exit flue 25. Furthermore as the cold air enters the intake 16 it travels over a vessel 21 in the chamber 20 provided with a door 19, where it is moistened. The arrows 26 indicate the travel of the heat from the combustion chamber as shown in Figure 3 and as deflected by the member 27.

In short, the flues 14 are heated to radiate and discharge the heated air or gas therein heated by the gas burner 15, thus forming

heat radiating passageways therebetween communicating respectively with the cold air intake and the hot air discharge flue 18, the products of combustion in the form of waste gases from the burner being safely conveyed by the flues 14 to the header 24 through the pipe 24¹ thence to the exit flue 25 by the flue 24, thus not only rendering the device safe but efficient in operation.

10 In the modified form as particularly illustrated in Figures 9 and 10, the improved air heater is made of individual units, which may be manufactured as such and when assembled form a complete air heater.

15 The casing or shell 10 is substantially the same as heretofore described, and has detachably secured therein by means of bolts or the like, the combustion chamber 28. This chamber in itself is substantially inverted V-shaped in formation and is provided with a lip 29 which may be secured to the casing 10 through the medium of the orifices 30 by any well known means.

20 Adjacent the upper portion of the chamber 28 are a plurality of flanged orifices 31 through which pass the hot gases of combustion. The elongated heat radiating members 32 are adapted to fit tightly against the wall 33 of the chamber 28, while the upper 25 portion will engage the flanges of the orifice 31.

25 Adjacent the centre of the flues 32 is a main flue pipe 34, while below the base thereof is a baffle member 35.

30 In operation the extension 36 of the fresh air pipe is preferably placed in contact with the outside air to ensure a constant supply of clean fresh air. The air passing through the opening 16 moves over the vessel 21 and 35 strikes the heat radiating surfaces of the member 32, where it is heated passing off through the outlet 18 to be distributed in any desired manner, while the hot gases of combustion pass through the opening 31 40 along the member 32 where they contact with and are deflected by the baffle 35 and finally are discharged through the flue 34.

45 The essential features of the modified form of air heater are the fact that each unit may be manufactured separately, in other words the housing, the cover therefor, the combustion chamber and radiating member, etc.,

may be manufactured as a part, and there assembled as a complete unit.

50 As many changes could be made in the above construction, and many apparently widely different embodiments of my invention, within the scope of the claims, constructed without departing from the spirit or scope thereof, it is intended that all matter contained in the accompanying specification and drawings shall be interpreted as 55 illustrative and not in a limiting sense.

What I claim as my invention is:

1. A fresh air heater comprising in combination, an outer casing, an inner casing spaced therefrom and adapted to provide a combustion chamber communicating with the inner casing, a header communicating with the opposite end of said casing, a plurality of substantially V-shaped flues communicating with the combustion chamber and the header, said flues being spaced from one another to form air passageways, air intake and discharge means communicating with said passageways, means for heating the combustion chamber and a discharge flue communicating with the header whereby the cold air passes through the passageways to be preheated and then discharged and whereby the heated gases pass through the flues to radiate heat to the air passageways and thence to the discharge flue through the header.

2. In a device of the character described and in combination, an outer casing and an inner casing in spaced relationship thereto, a combustion chamber in the inner casing, a cold air intake communicating with the inner casing, a plurality of flues communicating with the combustion chamber at one end, a discharge flue, a header communicating with the discharge flue and with the aforesaid flues, baffle means in said flue, a plurality of passageways formed between the flues and communicating with the cold air intake and means for moistening the air in transit from the cold air intake to said passageways, a hot air discharge pipe communicating directly with said passageways.

100 In witness whereof I have hereunto set my hand.

WILLIAM ANDREW SPARKS.
